(57) **CLAIM**

The ornamental design for a shower curtain hook, substantially as shown and described.

DESCRIPTION

FIG. 1 is an elevational view showing one side of the invention, the opposite side view being a mirror image of the side shown;

FIG. 2 is an elevational view showing the right end of the invention;

FIG. 3 is an elevational view of the left end of the invention;

FIG. 4 is an elevational view showing the top of the invention; and,

FIG. 5 is an elevational view showing the bottom of the invention.
